UNITED STATES PATENT OFFICE

106,801

DESIGN FOR A STORE FRONT

Hortense V. Lederer and Frederick Stanton, Chicago, Ill., assignors to Wimpy Grills of Illinois, Inc., Chicago, Ill., a corporation of Illinois

Application January 17, 1936, Serial No. 60,642

Term of patent 7 years

To all whom it may concern:

Be it known that we, Hortense V. Lederer and Frederick Stanton, both citizens of the United States, residing at Chicago, in the county of Cook and State of Illinois, have invented a new, original, and ornamental Design for Store Front, of which the following is a specification, reference being had to the accompanying drawing, forming part thereof.

Figures 1 and 2 are, respectively, elevational and side views of a store front, showing our new design.

We claim:

The ornamental design for a store front, as shown.

HORTENSE V. LEDERER.
FREDERICK STANTON.
